UNITED STATES PATENT OFFICE.

HARRY W. BOLENS, OF PORT WASHINGTON, WISCONSIN.

CHAIR-SEAT SPIDER.

1,247,625.

Specification of Letters Patent. Patented Nov. 27, 1917.

Application filed February 4, 1915. Serial No. 6,027.

To all whom it may concern:

Be it known that I, HARRY W. BOLENS, a citizen of the United States, and resident of Port Washington, in the county of Ozaukee and State of Wisconsin, have invented certain new and useful Improvements in Chair-Seat Spiders; and I do hereby declare that the following is a full, clear, and exact description thereof.

10 My invention refers to pressed steel chair irons and has for its object to provide a simple, durable, light one-piece saddle for the support of the spider arms and also a one-piece spindle-head upon which the saddle is mounted, the two members being 15 pressed into shape by simple die operations.

With the above objects in view the invention consists in certain peculiarities of construction and combination of parts as set 20 forth hereinafter with reference to the accompanying drawings and subsequently claimed.

In the drawings

Figure 1 represents a side elevation of a 25 seat spider embodying the features of my invention, with parts broken away and in section to more clearly illustrate various details of construction, the section being indicated by lines 1—1 of Figs. 2 and 3;

30 Fig. 2, a similar sectional view taken at a right-angle to that shown in Fig. 1, the section being indicated by line 2—2 of Fig. 1;

Fig. 3, a detailed sectional plan view of 35 the head portion of said spider mechanism, and

Fig. 4, a detailed plan view of a tension lever.

Referring by characters to the drawings, 40 1 represents a threaded spindle, the upper end of which extends through a central aperture of the head A. The head is formed from a pressed steel blank and in order to provide a bearing of the desired length for 45 the spindle, the said head has riveted or otherwise secured thereto a centrally apertured bowed plate 2, which aperture is in alignment with the head aperture and the spindle is confined between the spaced members by upsetting in the usual manner. The 50 head is formed with a base portion 3 which carries the central spindle aperture and said base portion is also provided with side slots 4, as best shown in Fig. 3. The transverse edges of the base portion of said head are 55 folded downwardly to form ears 5 just out-

side of the slots 4 and the rear edge of said base portion is formed with a recess 6 through which a tension bolt 7 extends, the connections of the same being hereinafter 60 described. At the center of the base portion 3 of the head the same is cut away in rectangular form upon three sides and the freed metal is bent upwardly to form a fulcrum lip 7.

65 The spider comprises a saddle B, which saddle is formed from a single blank having a transverse bridge piece 8 that terminates with downwardly folded wings 8' having narrow end portions 8'' which project 70 through the head slots 4 and are fulcrumed upon a rod 9 that is mounted in the ears 5 of the head. Thus it will be seen that the saddle is capable of rocking back and forth and its movement is limited by the end faces 75 of the slots 4. The bridge-piece of the saddle is centrally depressed to form a fore and aft channel 10 into which is seated the fore and aft spider arm 11, the said spider arm and channel being in parallel relation to the 80 downturned wings. Thus it will be seen that this spider arm, when seated, is riveted or otherwise secured to the bottom portion 10' of the channel and its upper edges are flush with or slightly below the upper plane 85 of the bridge-piece. The usual transverse spider arm 11' is fitted over the first mentioned spider arm and rests upon and is secured to the high portions of the bridge-piece 8 by rivets or other suitable means. 90 Hence it will be seen that the fore and aft spider 11, which is subjected to greatest strains, is firmly seated within a wall channel 95 whereby its rigidity is insured.

The head of the tension bolt 7 which projects above the base portion of the head A is fitted through an aperture in a tension lever 12 having a fulcrum finger 12' that engages the upturned lip 7'. The forward end of the tension lever 12 terminates with 100 a hook for engagement of one end of a coiled spring 14, the opposite end of the same being secured to a clip 14' which projects from the front end of the fore and aft spider arm 11.

105 The bolt 7 is in threaded union with a nut 14'', which nut engages the bottom face of the base portion of the head and serves to regulate the tension of the coiled spring 14.

110 From the foregoing description it is obvious that the chair iron so constructed as a whole is light and durable and that the

parts may be manufactured at a minimum cost both with reference to machine work and assemblage.

As best shown in Fig. 4, the tension lever 5 is apertured for the reception of the tension bolt 7 and the upper face of said lever is formed with a straight shoulder 12" for notched engagement with the straight face of the tension bolt head, whereby said bolt, 10 when seated within the lever, is held against rotation coincident to adjustment of the tension bolt 14".

I claim:

A chair iron comprising a spindle carried plate having one portion dished, an oppositely dished plate secured to the dished portion of the first plate, a spindle having one end reduced to form a shoulder, said reduced portion being passed through the 20 dished parts of the plates and headed, whereby said dished portions are held between the head of the spindle and said shoulder thereof, said spindle carried plate also being provided with longitudinal slots 25 in its side portions, depending ears at the sides of the last mentioned plate adjacent said slots, a pivot bolt carried by said ears,

a spider saddle plate bent into inverted U-shape, the lower ends of the legs of said plate being reduced in width, disposed through said slots in the spindle carried plate and fulcrumed on the pivot bolt, the intermediate portion of the spider saddle plate being inwardly off-set to form a spider arm receiving channel extending in the direction of the pivotal movement of said saddle plate, a spider arm seated within said channel and secured thereto, the top of said arm being flush with the top of the adjacent portion of the saddle plate, and 40 a second spider arm secured on the saddle plate and disposed transversely of the first spider arm, said second spider arm engaging the top of the first and forming a supplemental securing means therefor.

In testimony that I claim the foregoing I have hereunto set my hand at Milwaukee in the county of Milwaukee and State of Wisconsin in the presence of two witnesses.

HARRY W. BOLENS.
